UNITED STATES PATENT OFFICE.

CHARLES C. WRENSHALL, OF ST. PAUL, MINNESOTA.

FASTENING FOR CAR-DOORS.

SPECIFICATION forming part of Letters Patent No. 363,935, dated May 31, 1887.

Application filed March 14, 1887. Serial No. 230,821. (No model.)

To all whom it may concern:

Be it known that I, CHARLES C. WREN-
SHALL, of St. Paul, in the county of Ramsey and
State of Minnesota, have invented certain new
and useful Improvements in Fastenings for Car-
Doors, of which the following is a specification.

My invention relates to an improvement in
the means for fastening and securing the slid-
ing doors ordinarily used in freight-cars; and
it consists, generally, in the construction and
combination hereinafter described, and par-
ticularly pointed out in the claims.

In the drawings which form a part of this
specification, Figure 1 is a side elevation of a
portion of a car, showing the door with my im-
proved device attached thereto. Fig. 2 is a
vertical section of the same. Figs. 3, 4, and
5 are details.

In the drawings, 2 represents the car-door,
supported at the bottom upon rollers 4, which
travel upon the track 6, and at the top held in
position by guides 8, which slide upon the bar
10. These parts may all be of the ordinary
form of construction.

12 is a bar or bolt, preferably located cen-
trally upon the outer surface of the door and ar-
ranged to slide vertically in bearings 14, which
are attached to the door.

16 is a bar which extends horizontally below
the door, and may be secured to the body of the
car or to the track 6. The upper end of the
bolt 12 is preferably recessed to receive the
bar 10, and the lower end is U-shaped and ex-
tends under and embraces the bar 16. The
bars 10 and 16 are preferably provided with
notches 17 and 19, cut in their lower edges and
of a size to receive the ends of the bolt 12 when
brought in line with them. These notches may
be placed at any desired position upon the
bars, and as many of them as may be found
convenient. I prefer to construct the bars
with two sets of notches—one set to receive the
bolt when the car-door is open and one set to
receive it when the door is closed, as shown in
Fig. 1.

18 is a rectangular handle or operating-lever
held in bearings 20, which are secured to the
car-door and in which the said handle is free
to oscillate in a vertical direction. The por-
tion of the handle between the bearings 20 is

offset to form the crank 22. This crank is em-
braced by a strap, 24, which is also provided
with a hinge-joint, 26, to compensate for the re-
volving motion of the crank 22. The lower por-
tion of this hinge is secured to the bolt 12.

55

It will be seen that by oscillating the handle
18 motion will be imparted by means of the
crank 22, through the strap 24, to the bolt 12.

The lower section of the handle 18 is slotted
to receive a tongue or staple, 28, on the bolt 12.
This staple is preferably provided with pin-
holes to receive the pin 30, and this secures
the handle in its downward position. A lock
or car-seal may be attached to this staple and
the bolt then permanently locked or sealed.

65

The crank 22 is so formed as to bring the
offset above the center when the handle is in a
downward position. This allows the weight of
the handle 18 to act to keep the bolt 12 raised.

The operation is as follows: The door being
in the position shown in Fig. 1, the bolts 12 are
forced into the recesses 17. To open the door
the handle is raised. This causes the bolt 12
to be lowered until it is free from the notches
17. The door is then forced back to any de-
sired point.

Should it be desired to secure the door open
it is carried back until the bolt corresponds
with the notches 19, when the handle is brought
to its downward position, and this motion car-
ries the bolt upward and into the notches 19,
and the door is prevented from sliding until
the bolt is released. In closing the door again
the same operation is repeated and the lock
or car-seal attached to the staple, and the door
is securely fastened.

80

The weight of the handle holds the bolt in
engagement with its notches, both when the
door is opened and when it is closed.

When this device is used, it will be impossi-
ble for any one to pry the door open or remove
the staple that holds the lock. Another ad-
vantage is, that as the fastening and handle are
at the center of the door, it is easier to move
the door by grasping the handle than it is
when the handle is at one edge of the door, as
they are ordinarily placed. The handle 18
serves both as a lever for operating the sliding
bolt and as a handle for opening or closing the
door, so that a person can grasp the handle.

95

100

release the bolt, and open the door without letting go of the handle, or can likewise grasp the handle, close the door, and engage the bolt to fasten the door.

5 I claim as my invention and desire to secure by Letters Patent—

1. The combination, with the car-door, of the bars 10 and 16, having the notches 17 and 19, the vertically-sliding bolt 12, having its upper end adapted to engage the notches in the bar 10 and its lower U-shaped end adapted to engage the notches in the bar 16, and means for moving said bolt 12, substantially as described.

2. The combination, with the car-door, of the notched bars 10 and 16, the vertically-sliding bolt moving in guides upon the door and having its ends adapted to engage the notches in the bars, and the handle 18, having the crank bend 22 connected with the sliding bolt, substantially as described. 20

In testimony whereof I have hereunto set my hand this 9th day of March, 1887.

CHARLES C. WRENSHALL.

In presence of—

E. W. OSBORNE,
R. H. SANFORD.
